DISPLAY CABINET

Leslie S. Dorsey, New York, N. Y., assignor to National Gourmet Shops, Inc., New York, N. Y., a corporation of New York

Application October 31, 1951, Serial No. 17,190

Term of patent 3½ years

(Cl. D80—9)

To all whom it may concern:

Be it known that I, Leslie S. Dorsey, a citizen of the United States of America, residing at 143 East 62nd Street, New York, in the county and State of New York, have invented a new, original, and ornamental Design for a Display Cabinet, of which the following is a specification, reference being had to the accompanying drawings, forming a part thereof.

In the drawings,

Fig. 1 is a top plan view of a display cabinet, showing my new design;

Fig. 2 is a side elevational view corresponding to Fig. 1; and

Fig. 3 is an end elevational view corresponding to Figs. 1 and 2.

The side and end of the cabinet opposite that shown in Figs. 2 and 3 are identical to the side and end shown.

I claim:

The ornamental design for a display cabinet, substantially as shown and described.

LESLIE S. DORSEY.
